UNITED STATES PATENT OFFICE.

ELI M. GREENLEE, OF NEWPORT, KENTUCKY.

PROTECTOR FOR AUTOMOBILE STARTING-SWITCH BUTTONS.

Application filed July 30, 1925. Serial No. 47,143.

To all whom it may concern:

Be it known that I, ELI M. GREENLEE, a citizen of the United States, and residing at Newport, in the county of Campbell and State of Kentucky, have invented a new and useful Improvement in Protectors for Automobile Starting-Switch Buttons, of which the following specification is a full disclosure.

10 My invention relates to an appliance for locking an automobile engine starter switch against operation, to prevent the accidental or malicious use of the starting switch, and in particular to a protective covering or closure, adapted to be applied over the commercial starter switch buttons, protruding through the floor of an automobile, necessitating the use of a key for actuating the switch button.

15

20 An object of the invention is to provide a protective closure or covering on an electric switch button with a removable key, insertable through a latch controlled key opening or openings, for access to the switch button, the key utilized for actuating the switch button and securing the switch against operation or control when the key is removed.

25 Further objects and advantages will be 30 more fully set forth in the description of the drawing forming a part of this specification in which:

Figure 1 is a sectional view taken centrally of the cover and showing the cover as 35 applied over the starter switch button.

Figure 2 is a sectional view taken on line 2—2 of Fig. 1.

Figure 3 is a sectional view taken on line 3—3 of Fig. 1, showing the locking mechanism in the cap of the cover.

Figure 4 is a top plan view of the cover.

Figure 5 is a view taken the same as Fig. 1, but showing the key inserted in the casing and in position for operation of the 45 starter switch.

In the drawing, the appliance as an automobile engine starter switch button lock is 50 illustrated as a casing having a latch controlled key opening adapting a key to be inserted into the casing for engaging and depressing the switch button. The device is arranged to be readily applied over a type of engine starter switch button in commercial use, the switch button protruding from the floor of the automobile. The device however can be readily incorporated as

a part of the starter switch organization for original installation.

The casing or cover consists of a tubular body portion 1 closed at its upper end by a cap 2 and flanged at the base thereof as at 3, screws 4 being inserted through the flange for fastening the cover to the floor 5 of an automobile. The cap 5 is counterturned to engage into the bore of the casing and seat 6 against the upper edge of the casing and its lower face is grooved for receiving and mounting the locking means. The cap is fastened to the tubular body by any suitable means such as the screws 7.

A latch bar or member 7 is slidably mounted within a groove 8 in the lower side of the cap and is held within the groove 8 by a plate 9 held rigidly in lateral grooves in the cap below the latch member. Apertures 10, 11 are provided in the cap, the aperture 10 adapted to register with an aperture 12 in the latch member and the aperture 11 registering with a tapered notch 13 at the outer end of the latch member. A U-shaped key 14 having one limb thereof provided with a tapered offset point 15, the taper corresponding to the taper of the notch 13, and a second shorter length limb with a blank end 16.

As the key 14 is inserted in the apertures 10, 11, the point 15 strikes the notch 13 and translates the latch member to bring the aperture 12 in the latch member in registry with the aperture 10 in the cap. The limb 17 of the U-shaped key having the point 15, is slightly longer than the opposite limb so as to align the opening 10 and 12 before the rounded end 16 strikes the latch member. The rounded end 16 passes through an aperture in the plate 9 and engages the starter button 17. As further pressure is exerted upon the key, the button 17 is forced downward and the switch is operated. The opposite end of the latch member from the notched end has a downturned portion 18 contacted by the loose end of a strip of spring metal 19, this strip 19 being fastened at its lower end to the inner wall of the tubular casing. The metal strip returns the latch member to normal closed position when the key is withdrawn. The top 20 of the key is flattened to present a smooth contact surface.

Thus, a cover for the starter button is provided, preventing useless operation of the starter and the entrance of dirt into the starter switch through the button aperture

in the floor board, the cover also serving as a lock for the car inasmuch as the key is necessary to apply pressure to the starter button.

Having described my invention, I claim:

1. A closure for a motor starter switch button, comprising a casing having apertures through a wall thereof for key insertion, a latch member horizontally slidably mounted within said casing as a closure for said apertures, and a key engageable through said casing apertures arranged to actuate said latch member and engage a starter button enclosed by said casing.
2. In combination with a motor starter switch button, a closure about said button, a latch member mounted in said closure, and a removable key adapted to enter said casing for actuating said latch member and de-
20 pressing said starter button.
3. Closure means for a motor starter switch button comprising a casing, a latch member slidably mounted in said casing, apertures in said casing, a key adapted to en-
25 gage through said apertures for translating said latch member and actuating said starter button.
4. In combination with a motor starter switch button, a closure about said button, a latch member slidably mounted within said closure, a groove and an aperture in said latch member, apertures in said closure, one in registry with said notch and the other disaligned with the aperture of said latch member, a U-shaped key having one point adapted to engage the groove for translating the latch member and aligning the aperture in the latch member and the aperture in the closure for the entrance of the other point of the key, said key when further depressed, 40 actuating said starter button.
5. A closure for a motor starter switch button, comprising a casing having apertures through a wall thereof for key insertion, a latch member mounted in said casing 45 normally providing a closure for said apertures, and a key having different length shanks, one for advancedly engaging a respective casing aperture for actuating said latch, and a second for engaging with a starter 50 button housed by said casing.

In witness whereof, I hereunto subscribe my name.

ELI M. GREENLEE.
